VEST OR WAISTCOAT

Charles Emms, London, England

Application February 14, 1935, Serial No. 6,552
In Great Britain October 8, 1934

1 Claim. (Cl. 2-102)

This invention relates to vests suitable for evening dress and daytime wear.

The main object of the invention is to provide a dress vest of smart appearance in which the amount of tailoring (fitting) is reduced to a minimum.

Another object of the invention is to provide a waistcoat which can be tensioned round the waist and when used with a dress shirt will hold the latter in position without buckling.

Owing to the difficulty of obtaining a correct fit with an evening dress vest or waistcoat, more especially when a stiff fronted shirt is worn, it has been the practice in recent years to wear a backless vest which hangs from the neck and is adjustably secured by a strap at the back. While this form of vest is a considerable improvement over the ordinary type with a back it still does not prevent the faces of the vest from bulging.

When wearing evening dress little can be seen of the vest or waistcoat and in fact with a tail coat it is only the portion across the waist and appearing below the coat line that is visible, the remainder, that is the lapel portion being covered up by the breast pieces of the coat and thus my invention consists broadly in fashioning the vest in such a manner that it does not hang from the neck as in an ordinary or backless vest so that it is supported only by attachment round the waistline.

The waistcoat of this invention essentially includes a band which can be secured firmly around the waist of the wearer thereby overcoming any tendency to bulge, the band being fashioned and/or made at the front to simulate the appearance of an ordinary dress vest and fastened at the back by means of a strap or other suitable form of fastening. The fashioning of the band is carried out by providing an artificial line of join such as by means of a seam, together with buttons.

The waistcoat may comprise a front, which is formed in one or two pieces, as may be convenient according to the style of waistcoat required, and side pieces attached to the front and adapted to form the fastening or to which the fastening means are secured. When the front is in two pieces, preferably the edge of the outer or front piece is left unsewn so that it possesses a natural edge effect.

The front piece is provided with buttonholes to suit the style in question and preferably pockets are also formed therein.

Positioning loops or tags adapted for engagement with the braces and the top trouser buttons

may be attached to the back of the front piece, but these will not be found necessary.

The front piece may if necessary be provided with a suitable stiffening means and for example detachable bone stiffeners may be fitted.

The invention is illustrated in the accompanying drawings, in which Figure 1 is a perspective view of one style of dress vest constructed in accordance with the invention, Figure 2 being a detail perspective sectional view thereof.

Figure 3 is a front lay-out view on a smaller scale of an alternative style of dress vest constructed in accordance with the invention, Figure 4 being a part back view thereof on a larger scale.

Figure 5 is a front lay-out view showing a further style of dress vest.

Figures 6 and 7 are respectively a front and plan view on a larger scale of a modified form of the vest of Figure 3.

Figure 8 is a perspective view of a dress vest constructed in accordance with a further embodiment of the invention.

Figure 9 is a view of a vest similar to that shown in Figure 8.

Referring to the drawings, the dress vest is constructed in the form of a waist band indicated generally at A and adapted to be fastened around the waist of the wearer. While the band may be constructed in a single piece of material, in most cases it will be found more convenient to make up the waist band in three portions, the front B and side pieces C and D which are attached to the ends of the front.

The front of the band, or as shown in Figure 1 the front piece B, itself is provided with an artificial junction line, which in the embodiment of Figure 1 is obtained by the false buttons B' and their buttonholing, of which there are two rows G so as to simulate a double breasted vest.

In the embodiment of Figure 3, the artificial junction line is obtained by a seam B² in addition to the buttons and buttonholing, and by cutting the usual points B³ and a front opening B⁴.

It will be appreciated that the front piece B may consist of a single length of material according to the design as in the case of that shown in Figure 1 or it may consist of two pieces as in the case of the styles shown in Figures 3, 4 and 5, the two pieces being joined by a seam line at the front which gives the appearance of an opening.

The shape of the front is thus dependent upon the style of vest required. In Figure 1 the front

is straight and pleats E, which may be omitted, are provided.

To enhance the double breasted effect a separate piece of material may be sewn on to the front B extending between the dotted lines H or if the front is in two pieces one may overlap the other as in the Figure 5 style.

It is preferable, is not essential however, in order to obtain a smart effect, to construct the front 10 in effect as a single piece of material either from a one piece length or two pieces united by stitching in order that it may take the strain imposed upon it by the belt attachment without dragging at the buttonholes as would occur if the two 15 pieces buttoned together as in the case of the ordinary vest.

However if desired a buttoning effect may be obtained by providing a loose flap, which is held down by the buttons but has no pull upon it. 20 Thus in the double breasted style of Figure 5 the overlap may button down, the two pieces B actually being united by stitching down the centre.

The artificial buttons are conveniently detachable for the purpose of cleaning the vest and preferably therefore proper buttonholes G are formed in the front, there being two rows in the double breasted style of Figure 1 and a single row in Figure 3. In this case a protective flap of material H' is secured to the back of the front to form a pocket within which are the button securing clips.

The side pieces C and D, which may or may not be formed of the same material as the front, constitute the securing means, one piece having a series of holes I and the other a buckle J, which is detachably secured by buttons K.

While other forms of fastening, adjustable or otherwise may be fitted they should be such as to 40 give a firm purchase round the waist. A buckle fastening as illustrated, owing to the breadth of the buckle will fit into the hollow of the waist and transmit a pull throughout the width of the side pieces so that the entire vest front will sit flat 45 across the stomach.

A similar effect could be obtained by the small buckles spaced apart but this would not be so efficacious from the point of view of the wearer or of manufacture. For example the pieces C and D 50 may be of elastic material and it is not essential that they be made of the same length, in which case the fastening would be at the side.

F are pockets which however are not essential. It will be understood that either welt (Figures 1 55 and 3) or jetted (Figure 5) type pockets may be provided.

In certain styles it may be found convenient to have some form of stiffening means and for this purpose vertically extending pockets L are provided at the back for the reception of bone stiffeners M.

A buttonholed tag N (Figure 4) is attached to the back at the centre in order to locate the vest centrally, the tag buttoning on to the trouser buttons. O are loops which may be positioned to prevent the vest band from riding upwards, the loops engaging the trouser buttons. For the purpose of adjustability the tag N may be made to slide upon a tape extending across the back of 65 the front, the tape being secured by sewing in a position to suit the wearer.

The natural effect of the vest may be enhanced by constructing it in such a manner that the buttons will unfasten although the vest will not actually undo at the front. In this arrangement it is 70

necessary to make the front B from two separate pieces P and Q of material which are united by sewing along the seam B².

On the piece P are sewn the buttons B' while proper buttonholes G' are made in the piece Q. 5 Obviously in the case of a dress vest the buttons B' may be detachable as in the vest illustrated in the previous figures.

The advantage of this arrangement is that the edge R of the front piece Q will have what is 10 known as a natural edge thereby increasing the real appearance of the vest.

This natural edge effect can also be obtained without the buttons unbuttoning, by leaving the edge of the uppermost front piece which is the 15 right hand side as viewed from the front with a flap or loose edge indicated at R' (Figure 8).

According to a further feature of the invention the front of the vest may be detachable from the back. Such an arrangement is shown in Figures 8 and 9 in which the two pieces B constituting the front are detachably secured to a one piece back S which itself is adjustable.

In the arrangement shown in Figure 8 two buttons T are mounted on the ends of the back 25 piece for engagement with buttonholes T' in the front.

Preferably as shown the buttonholing is formed in the front piece so as not to interfere with the cleaning of the front, which when it becomes dirty 30 may be detached and sent to the cleaners.

A further advantage of this arrangement is that the wearer may possess several fronts to a single back so that he can change his style of front.

It will be appreciated that other forms of fastening, for example press stud, eyes and hooks, or a single hook and loop extending over the entire depth of the back may be employed. It is important however to space the attachment 40 means i. e. the buttons, a distance apart from each other so that they lie adjacent the edges since this ensures that the pull exerted by the back piece is transferred to the top and bottom edges of the front thereby maintaining an even 45 tension across the front of the vest and not a line tension across the centre which would cause the front to buckle more especially after it has been used several times.

Referring now to Figure 9 there is shown an alternate style of front in which the front is detachably secured to the back which is in two pieces as in Figures 1-3 by means of zip fastenings. It will be noted that the part of the zip fastening integral with the front is secured 50 to flaps U secured to the front pieces B and obviously this may apply to the buttonholing of Figure 8. A buckle fastening as shown in Figures 1 and 3 may be substituted for the zip fastening, the buckle being attachably secured to the flaps 60 U, in which case the two piece back with a buckle (adjustable) fastening as shown would not be necessary.

Where the back is in one piece a belt type of adjustment having a slide V may be provided, or 65 alternatively the back may be constructed of elastic material.

In order to allow the wearer a certain amount of give inserts of elastic material may be let into the back or back pieces of any of the forms of vest 70 illustrated.

It will be clear that the vest of this invention lends itself to the production of almost any style or design of dress vest or the like.

Although in the foregoing description and in 75

the accompanying drawings the invention has been described and illustrated mainly with reference to an evening dress vest, it will be obvious that the invention lends itself to waistcoats for daytime wear, particularly in the hot part of the year. Thus a vest may be cut in black silk or linen or other suitable materials and may be worn with a morning coat, or a single or double breasted jacket.

5 The vest of this invention will be found a distinct improvement upon the backless type of vest since once in position it does not require pulling or positioning, as the vest in whatever position the wearer may be whether sitting or standing, 10 will not be affected with the result that the wearer can go about assured of a tidy feeling about the 15 waist.

What I claim is:—

A dress or like vest constructed in the form of an open-ended body-encircling band having fastening means at its ends and comprising a narrow front section comprising overlapping portions stitched together and having its outer ends of lesser width than the center, narrow side straps directly connected by stitching to the ends of the front section, the upper edges of the straps being disposed in alinement with the upper edge of the front section, and the connections between the front section and the side straps being transversely flexible, and transverse stiffening means attached to the front section on opposite sides of and in close proximity to the center line of said front section. 5 10 15

CHARLES EMMS.
